Primary Examiner — Janice Hallmark*Assistant Examiner* — Rebecca Tsehay(57) **CLAIM**

The ornamental design for a hair dryer, as shown.

DESCRIPTION

FIG. 1 is a top perspective view of a hair dryer showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the encircled portion 9 in FIG. 1.

The broken lines are for the purpose of illustrating portions of the hair dryer that form no part of the claimed design. The dot-dash broken lines encircling portions of the claimed design that are illustrated in enlargements form no part of the claimed design.

1 Claim, 9 Drawing Sheets(56)
